Company, Hartford, Conn., trustee

Application July 13, 1944, Serial No. 544,791
In Great Britain September 23, 1942

8 Claims. (Cl. 171—119)

1

This invention relates to variable inductances of the kind comprising two coils usually connected in series and movable in relation to each other to effect the variation. The invention is concerned more particularly with variable inductances of this kind in which the coils are constructed and mounted so as to slide one within the other, e. g. are wound on cylindrical formers of different diameters and are arranged coaxially.

The object of the present invention is to provide an improved variable inductance comprising axially aligned and relatively movable sections, wherein the range of variation in inductance which can be achieved is similar to that normally achieved by the use of a fixed inductance and variable condenser; the relation between lowest and highest frequency is usually roughly 1:3 and if tuning is to be effected by a variable inductance the corresponding ratio between the inductance values is 1:9 which is far greater than can be attained with a two part coil having its parts arranged co-axially with one part sliding within the other. Such variable inductances are well adapted for ganging and afford a simple arrangement for tuning in wireless receiving apparatus.

According to the invention, with this object in view, the inductance consists of two co-axially mounted parts connected in series and in such manner as to provide positive mutual inductance between them and adapted to slide one within the other, and at least one of the two parts is rigidly connected with a co-axial auxiliary winding which when the two parts are one within the other in their position of maximum coupling is substantially without effect but when the two parts are moved apart the auxiliary winding rigidly connected with one of the parts assumes a position of maximum coupling in relation to the other part and reduces the total inductance.

In order that the invention may be more readily understood, it will now be described with reference to the accompanying drawing in which two embodiments of the invention are shown and in which:

Fig. 1 is a schematic diagram illustrating a coaxial coil arrangement for obtaining maximum coupling between two coils;

Fig. 2 is a schematic diagram illustrating a similar coaxial coil arrangement with minimum coupling between the two coils;

Fig. 3 is an exploded longitudinal sectional view of a coaxial coil arrangement for varying the coupling between the two coils;

2

Fig. 4 is a longitudinal sectional view of a coaxial coil according to the invention for varying the coupling between the two coils;

Fig. 5 is a schematic illustration of a second embodiment of the invention in which the coils are arranged for minimum coupling;

Fig. 6 is a schematic illustration of a second embodiment of the invention in which the coils are arranged for maximum coupling;

10 Fig. 7 is a sectional view of the second embodiment of the invention for varying the coupling between a pair of coaxial coils;

Fig. 8 is a schematic circuit arrangement showing the parallel connection of the coils illustrated in Fig. 5; and

15 Fig. 9 is a schematic circuit arrangement showing the series connection of the coils illustrated in Fig. 5.

The principle on which the embodiment of 20 Figs. 3 and 4 is based, will first be explained with reference to Figs. 1 and 2. Here, L_1 and L_2 are the two parts of the inductance which are mounted coaxially and are connected in series in such manner as to produce positive mutual inductance

25 between them. Associated with the part L_1 is a short circuited winding S_1 and associated with the part L_2 is a short circuited winding S_2 , the disposition of the components being such that when L_1 and L_2 are one within the other in the

30 position of maximum coupling (Fig. 1) the short circuited windings S_1 and S_2 are on opposite sides of the coupled parts L_1 and L_2 and are substantially without effect. On relative displacement into the position of minimum coupling (Fig. 2)

35 each of the parts L_1 and L_2 is closely coupled with the short circuited winding (S_2 and S_1) associated with the other, whereby coupling between L_1 and L_2 is substantially eliminated. The position of maximum coupling (Fig. 1) between L_1

40 and L_2 affords the maximum inductance value whereas the minimum inductance value is obtained when the positions are such that the short circuit windings have the maximum coupling with the inductances. Intermediate settings between Figs. 1 and 2 give corresponding intermediate inductance values. The short circuit windings S_1 and S_2 are most conveniently constituted

45 by metal cylinders or collars, preferably of copper. In the embodiment shown in Figs. 3 and 4 the part L_1 of the variable inductance is wound on a former F_1 to one end of which is secured a plate P serving to mount the variable inductance. Also secured to the plate P and extending into the former F_1 is a copper cylinder S_1 . The cylinder S_1

50

and the plate P are provided with a central aperture to receive the rod R on which the other part of the inductance is secured. The copper cylinder S₁ constitutes the short circuited winding associated with L₁ and the gap between S₁ and the former F₁ on which L₁ is wound is so dimensioned as to enable the former F₂, on which the other part L₂ of the inductance is wound, to pass into the gap. The former F₂ is secured to a copper cylinder S₂ which is co-axial with and rigidly secured to the rod R. This cylinder S₂ constitutes the short-circuited winding associated with L₂. The axial length of S₁ should be not less than the axial length of L₂, and similarly for S₂ and L₁. Fig. 3 shows the two parts L₁ and L₂ widely separated in order that the details of construction should be clearly seen. Fig. 4 shows an actual working position in which the total value of the inductance is a maximum. For smaller values, the rod R is moved to the right together with the copper cylinder S₂, the former F₂ and the part L₂ of the inductance. With this construction an induction ratio of at least 10:1 and a Q of approximately 50 can readily be attained. By disposing both S₁ and S₂ so as to be within the coils L₂ and L₁ with which they co-operate as shown in Figs. 3 and 4 it is found possible to achieve more favourable Q values than by arranging one inside and the other outside as in the explanatory diagrams of Figs. 1 and 2.

In the embodiment of Figs. 3 and 4, and in general for constructions based on the principle of Figs. 1 and 2, it is preferred that the parts L₁ and L₂ of the inductance should be of the same axial length and also have the same inductance value.

Referring now to the explanatory diagrams of Figs. 5 and 6, L₁ and L₂ have the same significance as before. However the coil L₂ has associated with it a supplementary coaxial coil L₃ which is secured in fixed relation to the coil L₂ and is electrically connected so as to produce negative mutual inductance effects with L₁. The coils L₂ and L₃ are preferably spaced axially by a distance equal to the axial length of L, and the arrangement is such that by relative axial movement between L₁ on the one hand and L₂ and L₃ on the other hand, L₁ may be disposed for maximum coupling with L₂ or with L₃ or in any intermediate position. Fig. 5 shows the minimum total inductance position and Fig. 6 shows the setting for maximum total inductance.

Fig. 7 shows a construction based on Figs. 5 and 6. In Fig. 7, the part L₁ of the inductance is wound on a former F₁, whereas the part L₂ and the supplementary coil L₃ are wound on a common former F₂ which is of external diameter to fit within the former F₁. By relative axial movement of F₁ and F₂ the part L₁ of the inductance can be brought into any desired position in relation to L₂ and L₃, between a minimum total inductance setting equivalent to Fig. 5 and a maximum total inductance setting equivalent to Fig. 6.

Advantageously the coils L₁, L₂ and L₃ all have the same axial length as shown in Fig. 7.

The coils L₂ and L₃ may be connected either in series or in parallel, but in either case the combination of L₂ and L₃ is connected in series with L₁. Fig. 8 shows the circuit arrangement when L₂ and L₃ are in parallel, and Fig. 9 shows a circuit arrangement when L₁, L₂ and L₃ are all in series. With a circuit as in Fig. 8 it is preferred that L₂ and L₃ should have the same inductance value, numerically equal to twice the value of L₁. With a circuit as in Fig. 9 it is preferred that

L₁, L₂ and L₃ should all have equal inductance values.

I claim:

1. A variable inductance comprising two coaxially mounted parts connected in series so as to provide positive mutual inductance between them and adapted to slide one within the other, at least one of said parts being rigidly connected with a coaxial short-circuited winding arranged to be substantially without effect when the two parts are one within the other in their position of maximum coupling, but to assume when the two parts are moved apart, a position of maximum coupling in relation to the other part whereby to reduce the total inductance.

2. A variable inductance comprising two coaxially mounted parts connected in series so as to provide positive mutual inductance between them and adapted to slide one within the other, at least one of said parts being rigidly connected with a coaxial short-circuited winding arranged to be substantially without effect when the two parts are one within the other in their position of maximum coupling, but to assume when the two parts are moved apart, a position of maximum coupling in relation to the other part whereby to reduce the total inductance, said short-circuited winding being provided in the form of a metal collar.

3. A variable inductance comprising two coaxially mounted parts connected in series so as to provide positive mutual inductance between them and adapted to slide one within the other, each of said parts being rigidly connected with a coaxial short-circuited winding arranged to be substantially without effect when the two parts are one within the other in their position of maximum coupling, but to assume when the two parts are moved apart, a position of maximum coupling in relation to the other part whereby to reduce the total inductance.

4. A variable inductance comprising two coaxially mounted parts connected in series so as to provide positive mutual inductance between them and adapted to slide one within the other, each of said parts being rigidly connected with a coaxial short-circuited winding arranged to be substantially without effect when the two parts are one within the other in their position of maximum coupling, but to assume when the two parts are moved apart, a position of maximum coupling in relation to the other part whereby to reduce the total inductance, said short-circuited winding being provided in the form of a metal collar.

5. A variable inductance comprising two coaxially mounted parts connected in series so as to provide positive mutual inductance between them and adapted to slide one within the other, each of said parts being rigidly connected with a coaxial short-circuited winding arranged to be substantially without effect when the two parts are one within the other in their position of maximum coupling, but to assume when the two parts are moved apart, a position of maximum coupling in relation to the other part whereby to reduce the total inductance, the short-circuited winding associated with the outer part being mounted within it at such spacing as to permit the passage of the inner part between the outer part and the short-circuited winding associated therewith.

6. A variable inductance comprising two coaxially mounted parts connected in series so as to provide positive mutual inductance between

them and adapted to slide one within the other, at least one of said parts being rigidly connected with a coaxial short-circuited winding arranged to be substantially without effect when the two parts are one within the other in their position of maximum coupling, but to assume when the two parts are moved apart, a position of maximum coupling in relation to the other part whereby to reduce the total inductance, the axial lengths of the two parts of the inductance and of the short-circuited winding being mutually equal.

7. A variable inductance comprising two coaxially mounted parts connected in series so as to provide positive mutual inductance between them and adapted to slide one within the other, each of said parts being rigidly connected with a coaxial short-circuited winding arranged to be substantially without effect when the two parts are one within the other in their position of maximum coupling, but to assume when the two parts are moved apart, a position of maximum coupling in relation to the other part whereby to reduce the total inductance, the axial lengths of the two parts of the inductance and of the short-circuited windings associated therewith being mutually equal.

8. A variable inductance comprising two tubular parts slidably arranged one within the other

for longitudinal displacement relative to one another, series-connected coils mounted on each of said parts and adapted to provide positive mutual inductance between them, a cylinder constituting one short-circuited winding connected to and arranged within the outer part spaced from the interior wall thereof, and a second cylinder constituting another short-circuited winding connected to and mounted on the inner part, the tubular portion of said inner part being adapted to slide into the space between the outer part and said first-named cylinder whereby each cylinder is positioned within the part of the inductance with which it cooperates.
